UNITED STATES PATENT OFFICE.

MILTON H. BALLARD, OF LYNN, MASSACHUSETTS, ASSIGNOR TO UNITED SHOE MACHINERY CORPORATION, OF PATERSON, NEW JERSEY, A CORPORATION OF NEW JERSEY.

STRIP-ATTACHING MEANS.

Application filed May 6, 1921. Serial No. 467,328.

This invention relates to machines for attaching welts or similar strips of stock to articles such as shoes, and is illustrated as embodied in an especially designed machine 5 for adhesively securing mock welts to soles for McKay shoes. An object of the invention is to improve such a strip-attaching machine, as hereinafter explained, although in various aspects the invention is not limited to embodiment in machines of the illustrated type.

At those parts of the shoe where the contour presents a sharp curve, as about the toe for example, the distortion of the laterally-bent welt presents a portion which is undesirably bunched or thickened and which in some cases is twisted out of the flat position which the welt must assume in the finished shoe. It has been proposed 15 to obviate this difficulty by the use of welts which are specially prepared to render them laterally flexible, or by slashing the twisted and bunched portions as the welt is flattened in a welt-beating machine, or by slashing or pinking the welts in the welt-stitching or welt-laying machines (for Goodyear, 20 welt and McKay shoes, respectively).

It is preferred, in handling McKay shoes and some styles of Goodyear shoes, to have the welt prepared for bending, by pinking or otherwise, in the welt-attaching machine, but when this is done it is found difficult to arrange the machine in a manner which will obviate great multiplication of 25 parts in the immediate vicinity of the point of attaching the welt. Recently it has been proposed to meet this difficulty by preparing the welt for bending while it is being fed to the attaching means, at a point so remote 30 that the welt preparing mechanism and the welt-attaching means are entirely separate, and do not join with one another to give this multiplicity of parts just at the point where the operator wishes to be as free as possible 35 to watch the actual attachment of the welt.

While this solution is usually satisfactory, it is found that in case the welt is prepared for bending in a way which necessitates accurate registration with the sharply-curved 40 portion of the shoe, difficulty is experienced in operating the preparing means at exactly

the right time so that the prepared portion of the welt will be fed forward into accurate registration with this portion of the shoe. For example, in laying mock welts on soles 55 for women's McKay shoes with pointed toes, it is desirable to prepare the welt for bending about the toe by "pinking", or removing a V-shaped section of the welt. Obviously the pinked section of such a welt must register exactly with the toe of the sole, and such accurate registration is difficult to secure when the time for performing the pinking operation is left entirely to the operator's judgment.

An important feature of this invention, accordingly, is to be found in the provision, in an apparatus for operating upon a portion of a welt or similar strip of stock and attaching the strip to an article, of means 60 to gage the location of the portion of the strip operated upon lengthwise with respect to the article to register said portion of the strip with a predetermined point on the article. As illustrated, a visual signal or gage 65 is provided, under the control of the operator, which indicates to him when he should operate the welt-preparing means, which is illustrated as a pinking device. The relative positions of the signal and the pinking device may be varied, to provide accurate adjustment, and the treadle which controls the signal is arranged with a lost-motion connection through which complete depression operates the pinking device.

Other features of the invention are to be found in a novel work support for use on pointed McKay soles such as described above, in an improved mounting of such a support to maintain at all times accurate parallelism 80 between the work-engaging parts of the support and the welt-attaching roll, and in various combinations and specific constructions which will be obvious from the following description of the embodiment of my invention 85 illustrated in the accompanying drawings, in which

Fig. 1 is a front elevation of the machine;

Fig. 2 is a side elevation of the upper 100 part of the machine, partly broken away;

Fig. 3 is a top plan view;

Fig. 4 is a perspective showing part of the operating mechanism;

Fig. 5 is a diagrammatic view showing the relation of the signal, the pinking device, and the welt-attaching means;

Fig. 6 shows a McKay outsole to which a mock welt has been adhesively secured by the machine;

Fig. 7 is a side elevation of a modification 10 embodying my novel pinking device;

Figs. 8 and 9 are detail views of the pinking device; and

Fig. 10 is a perspective of a welt from 15 which a section has been removed by the pinking device.

The illustrative embodiment of my invention shown in the drawings comprises generally a wheel 20 arranged to feed an adhesive-coated welt W past a pinking device 20 100 to a presser roll 22 where it is secured to a prepared, channeled, McKay sole S by the yielding pressure of a work support or feed roll 40, driven at a speed which is under the control of the operator. The pinking device 100 is manually actuated to remove a V-shaped section of the welt, as shown at X, Fig. 5, at a time when the toe of the sole registers with a signal or gage 80. The relative position of the rolls 22, 40, the pinking device 100, and the signal 80 is such that actuation of the pinking device at this time results in registering the prepared portion X of welt W with the toe 30 of the sole S (see Figs. 5 and 6).

To describe the machine more in detail, it comprises a base 24, illustrated as adapted to be secured to a bench, and the top of which is arranged in the usual way as a clamp adjustably to secure a plunger 26 carrying the machine proper. Power is derived from a suitable belt passing over pulley 28 through a hand-power clutch of the usual construction, arranged for more or less slippage so that shaft 30 is driven 40 by the pulley at the same speed handle 32 is rotated by the operator. Shaft 30 in turn drives gears 34 and 36, the latter meshing with gear 38, which drives presser wheel 22.

Gear 36 also drives shaft 42, carrying gear 44, which is arranged to drive the work support 40 through gears 46, 48 and 50. As best shown in Fig. 4, gears 46, 48 and 50, and the work support 40, are all mounted on a carrier 52 arranged for oscillation about a pivotal mounting 54, the maximum oscillation being too small to carry gears 46 and 44 out of mesh. The carrier 52 is pulled down by a suitable treadle, not shown, pulling on treadle rod 56, to facilitate the insertion and withdrawal of work between rolls 22 and 40, and is pressed upwardly toward presser roll 22 by spring 56 as far as permitted by an adjustable stop 58. The tension of spring 56 may be adjusted at 55

An edge guide for the sole is provided in the form of a roller 62 mounted on carrier 52 to remain constantly in co-operative relation to work-supporting roll 40 (Fig. 1).

By this novel mounting for work support 40 and its drive mechanism, it is maintained with its work-engaging surface parallel to the work-engaging surface of presser roll 22, regardless of its distance therefrom, and a constant and uniform pressure is at all 75 times attained throughout the width of the welt.

The work supporting roll 40 has a surface 64 to engage the upturned channel lip on the bottom of a McKay sole. In previous welt-laying machines the work-support has been mounted in a plane perpendicular to the plane of the sole, and the edge corresponding to surface 64 was therefore flat. Such a surface was found to bridge across some 80 of the sharper of the re-entrant angles formed at the shanks of McKay soles, particularly for certain styles of women's shoes, by the upturned channel lips, throwing both work-support and edge gage out of alignment with the welt. The welt, which remained in engagement with the edge gage, would accordingly be secured to such a sole with a portion projecting beyond its edge 85 at the shank.

To obviate this difficulty, I incline the plane of the work-support as shown, and form surface 64 as a frustum of a cone, so that its work-engaging portion will be perpendicular. By this arrangement, as will 90 be apparent from inspection of Figs. 1 and 5, the size of the work-engaging portion of roll 40 is so reduced that it will enter without difficulty the most extreme angle at the shank. 105

The side of work-support 40 opposite the lip-engaging surface 64 is cut away at 66 to provide clearance for the edge guide 62 (Fig. 5).

The signal 80 comprises a sole-registering member 82 movable longitudinally of the sole in a plunger 84, and clamped in adjusted position by a clamping bolt 86. This longitudinal movement provides for adjustment for various styles of shoes. This is necessary because the distance 80-40 measured about the contour of the sole must equal the distance 40-100 measured along the welt, and the contour distance 80-40, as compared to the straight line distance 80-40 which is what the position of member 82 actually measures, will of course vary to some extent in different styles. 115

Plunger 84 is movable laterally of the sole to adjust for soles of different swing, and is held by a set screw 88 in adjusted position on arm 90 carrying the signal. Arm 90 is rocked by a spring 92 and plunger 93 operated by a lever 94 as far as permitted by stops 96, to bring the signal into 125 130

and out of co-operative relation to the sole being welted.

The pinking device 100 comprises a head 102 to which any one of a series of interchangeable cutters 104 may be secured by screws 106. The cutter acts against a cutting block 108, and a stripper device 112 is yieldingly held in place by a spring 110. Head 102 is reciprocated to actuate the cutter by a pull-rod 114, actuated by a bell crank 116. Bell crank 116 is operated by pulling down on treadle rod 118 by means of a suitable treadle, not shown.

Lever 94 is also actuated by treadle rod 118, being pushed upwardly by a stop 120 thereon, to pull signal 80 up to idle position, and pushed downwardly by stop 122 acting through spring 124. After lever 94 engages the upper stop 96 when signal 80 is in active position, further downward pull on rod 118 merely compresses spring 124 without further operating lever 94, and operates the pinking device 100. Rod 114 is given sufficient lost motion to allow operation of signal 80 separately from the pinking device in this way.

In Figs. 7-10 there is shown a modification of the above-described machine embodying an illustrative form of my novel pinking device. This device comprises a straight knife 204 carried by a head 202 to permit ready exchange for a sharp knife, and a leaf spring 206 on each side of the knife to prevent the welt from sticking to it when cut. This knife is intended to sever a portion V from the welt by two successive cuts in different angular positions. Head 202 carrying the knife is turned to these positions by a gear 208 meshing with a segmental rack 210 carried by an arm 212 rocked by link 214. Link 214 is operated by a crank pin 216, mounted for radial adjustment in an undercut groove in a crank disk 218, secured to a spindle 220, and carrying a pawl 222. Spindle 220 is mounted to turn in a friction bearing 224 carried by a projection 226 of head 26, against the further resistance of friction washers 228. The friction of the bearing 224 and washers 228 holds crank disk 218 wherever it is turned.

Loosely mounted on spindle 220 is a gear 230 carrying a ratchet 232 co-operating with pawl 222, and meshing with a rack 234 on an arm 236 of the signal-operating arm 90.

By this arrangement, each time arm 90 is rocked, gear 230 turns ratchet 232 180° forward and then back. On the forward turn, one tooth of ratchet 232 engages pawl 222 and turns crank disk 218 through 180°. On the return turn of ratchet 232, pawl 222 is idle, and the friction of bearing 224 and washers 228 holds crank disk 218 stationary. Thus the disk turns constantly in a clockwise direction in Fig. 8, 180° each time arm 90 is

rocked, and each 180° turn rocks knife 204 from one side of the cut X to the other. As shown in Fig. 10, the two successive cuts which remove the section V are arranged to cross a very short distance from their ends, to provide a clean cut about the outline of the section V to insure its complete separation.

By adjusting pin 216 radially of cam disk 218, the throw of knife 204 may be varied, to change the width of the section V removed thereby.

In operating the modification of my invention shown in Figs. 1-6, the end W¹ of the welt is butted by the operator with a sharp knife, treadle rod 56 is pulled down to separate rolls 22 and 40, and a sole S is inserted against the adhesive-coated side of the welt. The operator, holding the sole in his left hand and handle 32 in his right, feeds the work along in the usual manner. Shortly after starting, he operates the other treadle to pull down on rod 118 just far enough to move signal 80 to active position. When the signal registers with the toe of the sole, as shown in Fig. 5, he stops feeding the sole long enough to pull treadle rod 118 the rest of the way down, pinking the welt at X, and then releases it to carry signal 80 and pinking device 100 back to their idle positions. On continuing the feeding of the sole S, the prepared portion X of the welt W registers exactly at the toe (Fig. 6). The operator lays the other side of the welt, and at the end of the operation he reverses handle 32 for an instant to feed the sole backward far enough to permit him to butt the end W² of the welt, whereupon he pulls down again on treadle rod 56 and removes the finished sole.

The operation of the second modification is the same, except for the pinking operation. The signal 80 having come into registration with the toe of the sole, as described, the operator first pulls rod 118 the rest of the way down, making one side of cut X, then releases it and immediately pulls it all the way down again. The first part of the second stroke turns knife 204 to the other side of cut X and the second part of the stroke makes the cut. Link 214 is mounted with sufficient play to allow for the reciprocation of the pinking device 200 as a whole in making the successive cuts. The signal 80 makes one useless motion from active to idle position and back at the time the second cut is made, but this is not of sufficient consequence to warrant separate treadle connections for the signal and the pinking device.

While I have described in detail one embodiment of my invention adapted for use in making McKay shoes, it is not the intention to limit its scope thereby, or otherwise than by the terms of the appended claims.

Having described my invention, what I claim as new and desire to secure by Letters Patent of the United States is:

1. In an apparatus for attaching a strip of stock to an article, in combination, means to attach a strip to an article, means to operate on the strip prior to attachment, and means to gage the location of the portion of the strip operated on lengthwise with respect to the edge of the article to register said portion with a predetermined point on the article.

2. In an apparatus for attaching a strip of stock to an article, in combination, means to attach a strip to an article, means to prepare a portion of the strip for bending prior to attachment, and means to gage the location of the prepared portion of the strip lengthwise with respect to the edge of the article to register said portion with a sharply curved portion of said edge.

3. In combination, means to attach a strip of stock to an article, a knife to cut the strip before attachment to facilitate bending it, and means to gage the location of the cut portion of the strip lengthwise with respect to the edge of the article to register the cut portion with a sharply curved portion of the article.

30 4. In an apparatus for attaching a strip of stock to an article, in combination, means for attaching the strip to an article, means for performing a preparatory operation on the strip before it is attached thereby, and a signal to facilitate the performance of the latter operation in a predetermined timed relation to the attaching operation.

5. In an apparatus for attaching a strip of stock to an article, in combination, means for attaching the strip to an article, means for performing a preparatory operation on the strip before it is attached thereby, and a signal for use in governing the performance of the preparatory operation, said signal being movable into and out of co-operative relation with the article.

6. In an apparatus of the class described, in combination, means to attach a strip of stock to an article, strip treating means operable in timed relation thereto, and a signal adapted to co-operate with the article for use in controlling said timed relation.

7. In combination, means to attach a strip of stock to an article, a treadle-controlled reciprocating knife to cut the strip prior to attachment, and a signal to indicate by its position relative to the article when the knife should be operated.

8. In combination, means to attach a strip of stock to an article, a knife movable to cut the strip prior to attachment, a signal to indicate by its position relative to the article when to operate the knife, and means to adjust the relative position of the knife and the signal.

9. In combination, means to attach a strip of stock to an article, means to prepare the strip for bending before attachment, a signal to indicate by its position relative to the article when the preparing means should be actuated, an arm to move the signal into co-operative relation with the article, and a treadle to control the movement of the arm.

10. In combination, means to attach a strip of stock to an article, means to prepare the strip for bending prior to attachment, a signal to indicate by its position relative to the article when the strip should be prepared for bending, an arm to move the signal into co-operative relation to the article, and means to adjust the position of the signal on the arm.

11. In an apparatus for attaching a strip of stock to an article, in combination, strip-attaching means, strip-cutting means spaced therefrom, and a device with which a given portion of the article is adapted to co-operate to afford a signal, said device being spaced from said strip-attaching means at such a distance that actuation of the strip-cutting means when a given portion of an article occupies a definite relation to said device will cause the cut portion of the strip to be attached to the given portion of the article.

12. In an apparatus for attaching a strip of stock to an article, in combination, a visual signal, a signal-actuating arm, a strip-cutting knife, a knife-actuating arm, and a member for moving said arms, said member being so connected to the arms that it moves the signal to active position without cutting the stock, and thereafter actuates the knife without further moving the signal.

13. In an apparatus for attaching a strip of stock to an article, in combination, a visual signal, a strip-cutting knife, and a member to move the signal from inactive to active position while moving the knife from inactive position to a preparatory position, and comprising a lost-motion connection to further move the knife to cut the strip without further moving the signal.

14. In an apparatus for attaching a strip of stock about the contour of a blank, in combination, means for pressing the stock against the blank, means for feeding the blank and stock relatively to said pressing means, a knife and a cutting block relatively movable to cut through the stock in the direction of said relative movement at points which are to be attached to a sharply curved portion of the blank, and manually-controlled means to vary the rate of feeding to permit slower feeding when the strip is being attached at said portions.

15. In an apparatus for attaching a strip of stock to a blank, in combination, strip-attaching means, means to cut a portion of a

- strip which is to be bent when attached to the blank, and a signal to show when said cutting means should be actuated to bring the cut portion of the strip on the portion 5 of the blank at which bending of the strip is desired.
16. In an apparatus for attaching a strip of stock to a blank, in combination, a support for a blank, a member to attach a strip 10 to a blank supported thereby, means to treat portions of the strip to prepare them for bending, and a signal to indicate by its relation to the blank the portions to be treated.
- 15 17. In an apparatus for attaching welts, in combination, means to attach a welt, means to treat the welt prior to attachment at points requiring bending, and a signal to indicate 20 when such a point has reached said treating means.
18. In a welt-treating apparatus, in combination, means to attach a welt, means to treat the welt prior to attachment at points requiring bending, and a signal to indicate 25 when such a point has reached said treating means, said signal being adjustable to register the treated portion of the welt with the desired point of attachment.
19. In an apparatus for attaching welts, 30 in combination with welt attaching means, means to treat a welt at a point to be bent, a signal to indicate when such a point has been reached, and an arm carrying the signal, the signal being adjustable longitudinally and laterally of said arm.
20. In an apparatus for attaching welts, 35 in combination with welt-attaching means, a knife to cut a welt at a point to be bent, a signal to indicate when such a point has been reached, and means to adjust the relative positions of the knife and the signal to change the point which is cut according to the shape of the article to which the welt is to be attached.
- 45 21. In an apparatus for attaching welts, in combination with welt attaching means, a knife to cut a welt, a signal to indicate when the welt should be cut thereby at a point requiring to be bent, and treadle-controlled 50 means to actuate the knife.
22. In an apparatus for attaching welts, in combination with welt attaching means, a welt-cutting device, a signal for determining when the device should be operated, 55 and a lever to actuate first the signal and then the welt-cutting device.
23. In an apparatus for attaching a welt 60 to a shoe part, in combination, welt-attaching means, means for treating a welt prior to its attachment to facilitate bending it, and means for indicating when such treatment should take place to bring the portion of the welt so treated in the desired position on the shoe part.
24. In a welt-attaching apparatus for use 65 in making shoes, in combination, welt-attaching means, manually controlled means for treating a welt at points requiring bending when attached, and a member to register with a portion of a shoe part to which a welt 70 is to be attached and so arranged that actuation of the welt-treating means when said portion registers with the member will result in attachment of the treated portion of the welt to said portion of the shoe part. 75
25. In a welt-treating apparatus, in combination, means to attach a welt to a shoe part, a gage spaced therefrom to register with a portion of a shoe part about which a welt is to be bent, and a welt-cutting device 80 spaced approximately the same distance therefrom, measuring backward along the welt strip, by which arrangement actuation of the cutting device will bring the cut portion of the welt on the registering portion 85 of the shoe part.
26. In a welt-attaching apparatus for use in making shoes, in combination, welt-attaching means, means to prepare a portion 90 of the welt for bending, and means to gage the location of the prepared portion of the welt relatively to the length of the sole edge to register said portion with the toe of a shoe.
27. In an apparatus for attaching a welt 95 to a shoe part, in combination, welt-attaching means, and means for notching the inner edge of the welt where it is to be bent in passing about the toe end of said shoe part.
28. In a welt-attaching apparatus, in combination, means to attach a welt to a shoe part, means to operate on the welt before it is attached, and a signal to indicate the time 100 for actuating said operating means.
29. In a welt-laying machine, in combination, means to guide a welt strip, a member having a surface to press the welt strip firmly against a sole, a rotatable member having a sole-supporting surface movable from an angular position relatively to the elements 105 of the welt-pressing surface into parallelism therewith as said member is rotated, a support to maintain one of said members in a fixed position, a lever to permit oscillation of the other member in a direction to right 110 angles to the elements of the work-engaging surfaces, and a spring to press said members together. 115
30. In a welt-laying machine, in combination, a welt laying roll, a sole-supporting roll having its axis inclined relatively to the plane of the sole, having a supporting surface whose elements are parallel when in supporting position to the elements of the surface of the welt-laying roll, and a support 120 for the rolls permitting them to be separated while maintaining the parallelism of the said elements. 125

31. In a welt-laying machine, in combination, a member to press a welt against a channeled sole, a roller edge gage to guide the sole, and a sole-supporting roll rotatable in a plane inclined to the plane of the sole and having a frusto-conical sole-supporting surface whose elements are parallel in supporting position to the plane of the sole, the inner side of the roll being cut away to provide clearance for the edge gage, and the outer side formed and arranged to engage the channel lip.

32. In a welt-laying machine, in combination, a member to press a welt against a channeled sole, and a support for the sole, comprising a roll rotatable in a plane inclined to the plane of the sole and having a frusto-conical sole-supporting surface made up of elements parallel in supporting position to the plane of the sole supported thereby, and having a second surface to engage the channel lip.

33. In a welt-laying apparatus, in combination, co-operating rolls to press a welt against a sole, a gage spaced therefrom and arranged to register with the toe of the sole during the laying of the first part of the welt, and a welt-cutting member spaced approximately the same distance from said rolls, measured back along the welt, to cut the part of the welt which is to be laid about the toe of the sole.

34. In a welt-attaching apparatus, in combination, an indicating signal, a manually-controlled lever to support and actuate said signal, and means to adjust in two directions the position of the signal on the lever.

35. In a welt-attaching apparatus having means to treat a welt, a gage to indicate when the treatment of the welt should be effected and comprising, in combination, a manually-controlled lever, a plunger having a portion longitudinally adjustable in said lever, and a signal adjustable on the plunger in a direction at right angles to the direction of the plunger adjustment.

36. In a machine of the class described, in combination, means to attach a strip to an article, a knife to cut the strip, a signal, means for moving the signal into position for use in controlling the cutting of the strip, and mechanism whereby the knife may be operated when a predetermined relation is established between the signal and the work.

37. In a machine of the class described, in combination, means to attach a strip to an article, a knife to cut the strip, a signal, means for positioning the signal for use in controlling the cutting of the strip, and means operative by further movement of the signal positioning means for actuating the knife.

38. A welt-laying machine comprising, in combination, welt-and-sole engaging presser and feed rolls, a knife for preparing for

bending a welt fed thereby, and means angularly to move the knife between successive cuts to vary its angular relation to the welt to enable it to remove a section of waste from the welt by such cuts.

39. A welt-attaching machine comprising, in combination, welt-attaching means, a knife for preparing for bending a welt attached thereby, and means to adjust the knife between its successive cuts to vary its angular relation to the welt in the plane of the welt.

40. A machine of the class described comprising, in combination, means for attaching a strip of stock to an article, a knife to operate on a portion of the strip before it is attached to the article, to prepare the strip for bending, and means angularly to move the knife between two successive positions for making angularly related cuts on the strip to remove a section of waste outlined by the angularly-related cuts.

41. A machine of the class described comprising, in combination, means for attaching a strip of stock to an article, a knife to make successive cuts in the strip before the strip is attached, means to move the knife toward and from the strip to make the cuts therein, and a lever and connections therefrom for adjusting the knife between successive cuts for different angular positions in the plane of the welt.

42. A welt-laying machine comprising, in combination, welt-and-sole pressing and feeding rolls, a roll to guide the welt thereto, a cutting block located between the guiding roll and the pressing rolls, and a knife movable into engagement with said block to cut the welt to prepare it for bending in attaching it to the sole.

43. A welt-laying machine comprising, in combination, welt-and-sole pressing and feeding means, a member to guide the welt thereto, a cutting block, and an operator-controlled knife located between the guiding member and the pressing means and movable into engagement with the cutting block to prepare the welt for bending in attaching it to the sole.

44. A welt-laying machine comprising, in combination, pressing and feeding rolls, a cutter to operate on a strip of welting before it reaches said rolls, a cutting block, and a treadle and connections therefrom for moving the knife into engagement with the cutting block.

45. In a welt-attaching apparatus, in combination, means for feeding a sole through the machine and attaching a welt strip to the sole as the sole is fed, means for operating upon an unattached portion of the welt strip at a point removed from the sole, and a gage to indicate by its relation to the sole when said operating means should be actuated to insure that the portion of the welt

strip operated upon shall bear a predetermined relation to the sole when attached thereto.

46. In a welt-attaching apparatus, in combination, means for feeding a sole through the machine and attaching a welt strip to the sole as the sole is fed, means for operating upon a portion of the welt strip before it is attached to the sole, and a gage arranged so

that a predetermined portion of the sole will 10 register with the gage to indicate when said operating means should be actuated to insure that the portion of the welt strip operated upon shall bear a predetermined relation to the sole when attached thereto. 15

In testimony whereof I have signed my name to this specification.

MILTON H. BALLARD.
